UNITED STATES PATENT OFFICE

JOHN HOEY, OF SAN FRANCISCO, CALIFORNIA.

BED-BOTTOM ATTACHMENT.

SPECIFICATION forming part of Letters Patent No. 663,170, dated December 4, 1900.

Application filed May 8, 1900. Serial No. 15,901. (No model.)

To all whom it may concern:

Be it known that I, JOHN HOEY, a citizen of the United States, residing in the city and county of San Francisco, State of California, 5 have invented an Improvement in Bed-Bottom Attachments; and I hereby declare the following to be a full, clear, and exact description of the same.

My invention relates to an attachment for 10 bed-bottoms of that class known as "wire" bed-bottoms.

It consists of the parts and the construction and combination of parts hereinafter described and claimed.

15 Figure 1 shows a bed-bottom with the side and end rails inclosed in one casting. Fig. 2 is an enlarged perspective view of one of the caps or housings.

In the construction of wire-mattress bed- 20 bottoms a framework is formed of the sides A, with transverse bars 2 at either end, these bars being supported at a sufficient height above the framework to allow the wire mattress 3 to be extended and stretched from one 25 to the other. In connection with this are the vertically-disposed spiral springs 4, resting upon the corrugated wires 5, which extend from one end of the bed to the other and also transversely from side to side, as shown. In 30 the usual construction of these beds it is difficult to make a proper finish for the ends of the transverse bars 2 and at the same time to carry the edges of the mattress to the full width which it is desirable they should occupy. As shown, the mattress 3 extends 35 over the top of the bars 2 and is bent down over the outer edges and is there secured by nailing on a supplemental covering-strip 6. The end of this strip and the end of the bar 40 2 make an undesirable appearance, and in my invention I have shown the ornamental covering and finishing cap, which includes the parallel horizontal flanges 8, the vertical longitudinally-extending flange or plate 7, and 45 the vertical transverse flange connecting the horizontal flanges, said flanges, with the plate 7, forming a housing which is secured to the ends of the bars 2 and 6, thus covering them.

In order to allow the wire mattress 3 to extend as far as possible outwardly on the sides, 50 these plates 7 have inwardly-projecting par-

allel horizontal flanges 8, which form a sort of housing within which the ends of the bars 2 are fitted and where they are properly secured; but in order to allow the edge of the 55 mattress 3 to be carried out to the full width of the bed the upper flanges 8 of these housings are cut away from about the center of the length of the plate 7 to the outer end, leaving a space, as shown at 9, where only the 60 thickness of the vertical portion of the plate 7 appears. This allows the edge of the mattress to pass over the flange 8 and to lie close against the edge of the vertical portion at 9, the end extending and being secured between 65 the parts 2 and 6, as before described.

In order to maintain the edge of the mattress with sufficient rigidity and prevent it from breaking down, a wire 10 is extended 70 through the loops or weave of the mattress 3, and this wire is secured at each end to the hooks 11. The position of these hooks is an important feature in my invention. They are made upon the vertical transverse flanges which connect the flanges 8 and form one 75 wall of the housing for the end bar, and they lie below the level of the upper surface of the upper flange 8, so that they do not form any projection which is unsightly and which is liable to catch the clothing or hurt the 80 hands of those working about the bed. The longitudinal pull and strain upon the mattress is borne by the transverse bars 2; but as the ends of these bars fit into the housing and as this is connected with the part 13, in 85 which the side rails A are fitted, these housings receive the strain and provide a rigid resistance thereto.

I have shown an extension or housing below the part 7 and including the parallel 90 horizontal flanges 13, which forms a cap inclosing and fitting over the ends of the timbers A. I also form a bridge or extension 14, which serves to raise the transverse timbers 2 to the proper height above the level of the 95 timbers A.

The device forms a neat finish for beds of this class in addition to the mechanical advantage of its construction as previously described.

When wire mattresses are made with a cable edge or the like, so that the whole end of

the wire mattress can be secured by the strip 6, the hook 11 and the inwardly-extending flange 8 may be omitted, having only the exterior face-plate 7 in the upper portion of the 5 attachment, the lower parts remaining the same, as shown.

Having thus described my invention, what I claim as new, and desire to secure by Letters Patent, is—

- 10 1. The combination with a wire bed-bottom including a mattress; longitudinal side bars and transverse end bars; of caps including a double series of parallel horizontal flanges and vertical transverse flanges connecting 15 the same and forming housings for the ends of both the side bars and end bars, said caps having vertically-disposed exterior covering-plates and the uppermost horizontal flange of each cap terminating short of the outer 20 end of the companion flange to enable the edges of the mattress to be brought out flush with the ends of the end bars so that said

edges may be extended over the uppermost flange of the cap.

2. The combination with the side rails and 25 transverse bars of a bed-bottom, of a cap or housing for said bars including a double series of parallel horizontal flanges, one series of flanges forming a housing for the end bar and the other series forming a housing for 30 the side rail said latter housing having its flanges extended beyond those of the other series, vertical transverse end flanges connecting the horizontal flanges, said cap or housing having a centrally-located bridge or 35 extension for raising the end bars above the side rails, and having an exterior covering-plate.

In witness whereof I have hereunto set my hand.

JOHN HOEY.
